UNITED STATES PATENT OFFICE

KARL MAIER, OF STUTTGART, GERMANY, ASSIGNOR TO UNION SPECIAL MASCHINEN-FABRIK, G. M. B. H., OF STUTTGART, GERMANY

OVEREDGE SEWING MACHINE

Application filed February 28, 1927, Serial No. 171,563, and in Germany March 25, 1926.

The invention relates to new and useful improvements in sewing machines, and more particularly to a sewing machine for forming overedge stitches.

An object of the invention is to provide a sewing machine of the above type having means for holding the interlocked thread loops laid over the edge of the material, with means for shifting said holding means for the thread loops while the machine is in operation.

A further object of the invention is to provide a machine of the above type having a thread drawing means for the overedge thread, with means for varying the amount of thread drawn off to correspond to the position of the holding means for the thread loops.

A further object of the invention is to provide a machine of the above character having a tension through which the overedge thread is led, with means for automatically varying the tension as the thread holding means is adjusted.

A further object of the invention is to provide a sewing machine of the above type having means for shifting the thread loop holding means, the thread drawing means, and varying the tension on the thread, with means whereby the position of the thread loop holding means may be shifted relative to the thread drawing and tension varying means.

These and other objects will in part be obvious and will in part be hereinafter more fully disclosed.

In the drawings—

Figure 1 is a view partly in section and partly in front elevation, showing a machine embodying the improvements;

Fig. 2 is a plan view of the machine directly above the work support;

Fig. 3 is a sectional view on the line A—B of Fig. 1;

Fig. 4 is a view of a portion of the machine from the rear of the machine, and showing the means for varying the tension on the thread;

Fig. 5 is a front view of the thread drawing off device when at one extreme end of its stroke;

Fig. 6 is a similar view showing the thread drawing device at the other end of its stroke;

Fig. 7 is a view of the thread drawing off device at the opposite end of its stroke from that shown in Fig. 1;

Fig. 8 is a plan view on an enlarged scale showing one form of article produced by the machine;

Fig. 9 is a similar view, but showing the overedge thread loops as very much lengthened by the shifting of the holding means for the thread loops;

Fig. 10 is a plan view showing a hat with a hat brim attaching ribbon applied thereto, which was formed on the machine;

Fig. 11 is a sectional view on the line C—D of Fig. 10;

Fig. 12 is a sectional view on the line E—F of Fig. 10, and

Fig. 13 shows diagrammatically a pattern seam which can be made by the improved machine.

The invention is directed broadly to a machine for forming overedge stitches, wherein the overedge thread loops are held by means which determine the length of these overedge thread loops when the stitches are set. The means for forming the overedge thread loops may be of any desired character, and the means for holding the overedge thread loops may be of different types. In one form of the invention, a finger is provided around which the thread loops are laid, and against which they are drawn when the stitches are set. This finger is carried by a swinging arm which is shifted manually during the running of the machine, if desired, for varying the lengths of the overedge thread loops. This enables various patterns or characters of overedge seams to be made. The finger is shifted by a rock shaft which may be operated by a pattern cam, or which may be operated by a suitable knee shift or treadle controlled device. The machine is also provided with means for drawing off thread for an overedge thread loop, and devices are also provided whereby the amount of thread drawn off may be varied by the position of the finger around which the overedge thread loops are formed. A tension is provided for

55

the thread forming the overedge thread loops, and means is also provided whereby this tension may be varied to accord with the position of the finger around which the overedge thread loops are laid.

Referring more in detail to the drawings, the machine consists of the usual supporting bed having a standard rising therefrom which carries an overhanging arm 1. Mounted to reciprocate in the free end of the overhanging arm 1 is a needle bar, which is provided with a needle 3. Mounted on the bed is a work support carrying a throat plate 2. This throat plate 2 is provided with the usual feed slots through which the feed dog operates. Cooperating with the needle 3 beneath the work support is a thread carrying member 3^a, and cooperating with this thread carrying member 3^a, is an overedge thread carrying looper 4, which forms an overedge thread loop and positions the same so that it is locked by the needle thread loops as they are formed by the needle. The features just described are very common in an overedge sewing machine, and further detail description thereof is not thought necessary.

Adjacent the needle is a finger 5 carried by a bracket arm 7 pivoted at 6 to the cloth plate of the machine. This finger lies alongside of the needle 3, and is so positioned that the overedge thread loops are laid over this finger, and when they are drawn down to set the stitches, they are drawn against the finger. The position of the finger regulates the length of the overedge thread loops, and thus it might be called the width of the overedge stitch.

This bracket 7 is capable of being shifted on its pivotal support. This is accomplished by a link 8 which is pivoted to an arm 9 carried by a rock shaft 10. The rock shaft 10 carries an arm 11 which may be connected to a treadle, a knee shift, or to a pattern cam, if desired, so that the arm 11 can be shifted automatically or manually, at will. The arm can be manually shifted at will, or automatically shifted, during the running of the machine, if desired. When this arm 11 is shifted it will rock the shaft 10, and through the link 8 will shift the finger 5. In Fig. 2 of the drawings, the finger is shown in full lines in one position and in dotted lines in another position.

In Fig. 13 of the drawings, there is shown diagrammatically, an edging seam S, which can be made on the above machine by a shifting of the finger 5. It will be noted from this figure of the drawings that the needle forms the thread loops at the left of the figure, while the overedge loops are interlocked at s' at the right of the seam in the waved line. This is due to the fact that the finger has gradually moved away from the needle and then gradually moved toward the needle, thus forming, in effect, a scalloped edge.

It will be noted that the finger 5 is separate from the bracket arm 7 and is secured thereto by a screw 5^a, so that the finger may be removed from the machine. The bracket arm 7 is provided with a guiding recess 17 which enables a wire or rod or a similar element to be guided by this recess 17 alongside of the needle. In this case, the rod or wire or element which passes through the recess 17 serves as a means around which the thread loops are formed. The thread loops do not pass off from the end of the wire or rod, but the rod goes through the machine and becomes a part of the article which is formed on the machine. Here again, the shifting of the bracket arm 7 will vary the position of the rod or wire relative to the needle, and thus vary the length of the overedge thread loops. Thus it is that the machine becomes particularly useful for forming an edging for the brim of a hat. In Fig. 10 of the drawings, a hat is shown at 13, which hat is provided with the usual brim 12.

An edging ribbon is indicated at 14. On the interior of the hat rim there is a resilient rim 15 of steel wire or the like. The machine may be used for forming the edging for a hat by guiding the resilient rim 15 through the recess 17 in the bracket arm 7, and by directing the edging ribbon 14 through a suitable guiding channel so that the needle will pass thread loops through the edge of the ribbon. As shown in Figures 1 and 2 of the drawings, this guiding channel is formed by a plate 50 which is provided with a guiding rib 16 at the end thereof adjacent the needle, and with an adjustable edge guiding plate 18. Screws 19 pass through slots in the plate 18 and serve as a means for holding the plate in adjusted positions, so that the guiding channel for the ribbon may be varied as to width in order to accommodate the desired width of ribbon. A cover member 38 hinged to the plate 50 may be used, and a spring 51 provided for holding this cover plate 38 down on the ribbon, as clearly shown in Fig. 2 of the drawings. This merely closes the channel, and the ribbon runs through the guiding channel beneath this cover plate 38. The cover plate may be readily raised to remove the ribbon or replace the ribbon whenever desired.

In Fig. 8 of the drawings, the ribbon 14 is shown as secured to the rim 15 by overedge stitches which include needle thread loops n and looper thread loops l, l'. These needle loops pass through the edge of the ribbon, and the looper threads are carried laterally to a position so that the thread loops in the looper threads l, l' may pass around the rim 15. It will be noted that at one part in the edging ribbon for the hat, the rim should be close to the ribbon, while at another point in the edging ribbon, the rim should be at a considerable distance from

the ribbon. This is accomplished by manually shifting the arm 7, and thus lengthening the overedge thread loops, as shown in Fig. 9. The length of the thread loops is varied merely by the position of the steel wire rim 15.

It will be obvious, of course, that many other articles can be formed on my improved machine by using this manually shiftable bracket arm provided with means around which the thread loops are formed and drawn up.

Each looper thread l, l' is led from the supply through a tension 23. This tension consists of the usual tension disks, which are held pressed one against the other by a spring 24. The tension disks and the spring are all mounted on a rod 26, and nuts 25 may be used for varying the tension of the spring against the tension disks. After leaving the tension disk 23, the looper thread passes through a thread eye 21 carried by an arm which is fixed to the rock shaft 10. It is then led through a thread guide 20 carried at the lower end of the needle lever extension 22. From this point the thread passes to the thread carrying looper. As the needle lever oscillates, the thread guide 20 will be moved toward and from the thread guide 21, and it will be obvious that the amount of thread drawn off will depend upon the position of the thread guide 21. This thread guide 21 being carried by the rock shaft 10, is shifted when the rock shaft is oscillated.

When the rock shaft is oscillated, the bracket arm 7 is shifted, and therefore, the position of the thread guide 21 will be automatically varied by the shifting of the bracket arm 7. Starting with the parts as positioned in Fig.

1, let it be assumed that the arm 11 remains in the position indicated in this figure, for a stitch cycle. During that time, the thread guide 21 will remain in a fixed position. As the needle rises, the thread guide 20 will be

45 moved to the left, as viewed in this figure, and to the position indicated in Fig. 5. As the needle comes down, then the thread guide 21 will move again to the right. When the parts again reach the position shown in Fig.

50 1, the center lines of the thread guides 21 and 20, indicated at a and b , will coincide. That is, the thread guide 20 has moved from the line a , Fig. 5, to the line b , Fig. 5, in a direction indicated by the arrow X , and has

55 covered a distance indicated by A. During this movement, there has been no drawing effect on the looper thread. It has been what might be called an idle movement. As the needle continues its down stroke, the needle lever extension 22 will continue to move to the right to the position shown in Fig. 6. The center line b of the thread guide 20 has moved away from the center line a of the thread guide 21, a distance indicated at B,

60 and this draws on the thread and pulls thread

through the tension from the supply. It will readily be seen that by shifting the arm 11, the thread guide 21 will be shifted and the amount of thread drawn off will be varied. For example, when the thread guide 21 is shifted to the position shown in Fig. 7, then the distance between the center line a and the center line b will be less, as indicated at C.

Means has been provided for varying the tension on the looper thread when the bracket arm 7 is shifted. This is accomplished by providing a cam 27 which is attached to an arm 35 by screws 37. The arm 35 is fixed to the shaft 10. Extending through the standard of the machine is a rod 29. This rod 29 is mounted in a bearing sleeve 28, and the end of the rod 29 is mounted and positioned so as to engage the cam 27. The rod at its other end, carries a plate 30 which is forked so as to straddle the rod 26 on which the tension disks 23 are mounted. This plate 30 serves as an abutment against which the tension disks 23 are held pressed together by a spring 24, and of course, if the forked plate 30 is shifted, the tension on the thread will be varied. In Fig. 1 of the drawings, I have shown two tensions 23, and the plate 30 has a fork at each end thereof, one for each tension. This second tension would be used provided the lower thread carrying element of the stitch forming mechanism is a threaded element.

A spring 36 secured to the bed of the machine and to the arm 35 normally operates to turn the rock shaft 10 in a clockwise direction. At the back of the machine, there is a post 33 provided with stop collars 34, and the lower stop collar limits the downward movement of the cam through the action of this spring. The upper stop collar 34 limits the downward movement of the free end of the arm 11.

The link 8 as clearly shown in Fig. 1, is made in sections, and these sections are joined by a sleeve 31. The set screws 32 attach the sections of the link to the sleeve. By loosening these set screws, the link may be lengthened or shortened, and thus the bracket arm 7 properly positioned relative to the set position of the rock shaft 10 determined by the stops 34.

From the above it will be apparent that I have provided an overedge sewing machine having means for regulating the length of the overedge thread loops, which means can be manually shifted at will, and I have also provided automatic means for varying the amount of thread drawn off and the tension on the thread, as the holding means for the overedge thread loops is shifted, so that the thread drawn off and the tension on the thread may be adapted to the proper length of overedge thread loop.

It is obvious that minor changes in the

details of construction and the arrangement of the parts may be made without departing from the spirit of the invention as set forth in the appended claims.

Having thus described the invention, what I claim as new and desire to secure by Letters-Patent, is—

1. The combination of cooperating stitch forming elements for forming overedge thread loops, means for holding said overedge thread loops when the stitches are set, means whereby said thread loop holding means can be shifted laterally for varying the position of the holding means during the running of the machine, means independent of the stitch forming elements for drawing thread from the supply for the overedge thread loops, and means for varying the amount of thread drawn from the supply to correspond with the position of the means for varying the overedge thread loops.
2. The combination of cooperating stitch forming elements for forming overedge thread loops, means for holding said overedge thread loops when the stitches are set, means whereby said thread loop holding means can be shifted laterally for varying the position of the holding means during the running of the machine, a tension for the thread forming the overedge thread loops, means for varying the tension on the thread when the thread holding means is shifted, means for drawing thread through the tension from the supply, and means independent of the stitch forming elements for varying the amount of thread drawn from the supply to correspond with the positioning of the holding means for the overedge thread loops.
3. The combination of stitching mechanism having means for forming overedge thread loops, means for holding said overedge thread loops when the stitches are set, means whereby said thread loop holding means can be shifted for varying the position of the holding means during the running of the machine, a tension for the thread forming the overedge thread loops, means for drawing said thread through the tension from the supply, said means for shifting the holding means for the overedge thread loops including a rock shaft, said means for drawing the thread from the supply having a thread eye positioned by said rock shaft, a cam for varying the tension on the thread, and means carried by the rock shaft for positioning said cam, whereby when said rock shaft is oscillated to vary the position of the thread loop holding means, the tension is varied and the amount of thread drawn off is varied to correspond with the positioning of said holding means.

4. An overedge sewing machine comprising stitching mechanism including a needle, a bracket arm, means for pivotally supporting said bracket arm, a finger carried by said bracket arm and located alongside of said

needle whereby the overedge stitches are formed around said finger, means for shifting said bracket arm for varying the position of said finger relative to the needle during the running of the machine, said last-named means including a rock shaft, a manually controlled arm attached to said rock shaft for oscillating the same, a spring for turning said rock shaft in one direction, stops for limiting the movement of the rock shaft, and a link connecting the rock shaft to said bracket arm including devices whereby said link may be lengthened or shortened.

5. An overedge sewing machine comprising stitch forming mechanism including a needle, a bracket arm, means for pivotally supporting said bracket arm, means carried by said bracket arm and extending alongside of the needle around which the overedge stitches may be formed, a rock shaft having an arm connected to said bracket arm for shifting the same when the rock shaft is oscillated, means whereby said rock shaft may be oscillated, means for drawing an overedge thread from the supply including a thread guide carried by said rock shaft whereby when said rock shaft is oscillated to shift the bracket arm, said thread guide is also shifted, and the amount of thread drawn off from the supply varied to accord with the position of the bracket arm.

6. An overedge sewing machine comprising stitch forming mechanism including a needle, a bracket arm, means for pivotally supporting said bracket arm, means carried by said bracket arm and extending alongside of the needle around which the overedge stitches may be formed, a rock shaft having an arm connected to said bracket arm for shifting the same when the rock shaft is oscillated, means whereby said rock shaft may be oscillated, means for drawing an overedge thread from the supply including a thread guide carried by said rock shaft whereby when said rock shaft is oscillated to shift the bracket arm, said thread guide is also shifted, and the amount of thread drawn off from the supply varied to accord with the position of the bracket arm, a tension for the overedge thread, and means carried by said rock shaft for varying the tension when the bracket arm is shifted.

7. An overedge sewing machine comprising stitch forming mechanism including a needle, a bracket arm, means for pivotally supporting said bracket arm, means carried by said bracket arm and extending alongside of the needle over which the overedge thread loops are laid, means for guiding a body fabric to said needle, manually controlled means for shifting the position of said bracket arm laterally for varying the length of the thread loops in the overedge stitches, said last-named means including a rock shaft, a link, connecting said rock shaft to said bracket arm.

et arm, a spring for oscillating said rock shaft in one direction, means whereby said rock shaft may be oscillated in the opposite direction, and stops for limiting the movement 5 of the rock shaft, said link having means whereby the same may be lengthened or shortened.

8. The combination of stitch forming elements for forming overedge thread loops, 10 means for holding said overedge thread loops when the stitches are set, means whereby said thread loop holding means can be shifted laterally for regulating the size of the formed thread loops, means independent of the stitch 15 forming elements for drawing thread from the supply for the overedge thread loops, and means for simultaneously shifting the thread loop holding means and varying the amount of thread drawn from the supply to correspond with the position of the holding means. 20

9. The combination of stitch forming elements for forming overedge thread loops, means for holding said overedge thread loops when the stitches are set, means whereby said 25 thread loop holding means can be shifted laterally for regulating the size of the formed thread loops, means independent of the stitch forming elements for drawing thread from the supply for the overedge thread loops, a 30 tension from the thread forming the overedge thread loops, means for simultaneously shifting the thread loop holding means, varying the tension on the thread, and varying the amount of thread drawn from the supply to correspond with the position of the holding means. 35

10. The combination of a stitch forming mechanism having means for forming overedge thread loops, means for holding said 40 overedge thread loops when the stitches are set, means whereby said thread loop holding means can be shifted laterally for regulating the size of the formed thread loops, means for drawing thread from the supply for the 45 overedge thread loops, means for simultaneously shifting the thread loop holding means and varying the amount of thread drawn from the supply to correspond with the position of the holding means, said last named 50 means including a lever, a spring for moving the lever in one direction, means for manually moving the lever in the opposite direction, and stops for limiting the movement of the lever. 55

11. The combination of a stitch forming mechanism having means for forming overedge thread loops, means for holding said overedge thread loops when the stitches are set, means whereby said thread loop holding 60 means can be shifted laterally for regulating the size of the formed thread loops, means for drawing thread from the supply for the overedge thread loops, a tension from the thread forming the overedge thread loops, 65 means for simultaneously shifting the thread

loop holding means, varying the tension on the thread, means for varying the amount of thread drawn from the supply to correspond with the position of the holding means, said last named means including a lever, a spring for moving the lever in one direction, means for manually moving the lever in the opposite direction, and stops for limiting the movement of the lever. 70

In testimony whereof, I affix my signature. 75
KARL MAIER.
